UNITED STATES PATENT OFFICE

AUGUSTUS J. FRAME, OF COLUMBUS, OHIO, ASSIGNOR TO COLUMBUS AUTO BRASS COMPANY, OF COLUMBUS, OHIO, A CORPORATION OF OHIO

DESIGN FOR AN AUTOMOBILE HEAD LAMP VISOR

Application filed May 18, 1931. Serial No. 39,881. Term of patent 14 years.

To all whom it may concern:

Be it known that I, AUGUSTUS J. FRAME, a citizen of the United States, and a resident of Columbus, county of Franklin and State of Ohio, have invented a new, original, and ornamental Design for an Automobile Head Lamp Visor, of which the following is a specification, reference being had to the accompanying drawings forming a part thereof.

In said annexed drawings:

Figure 1 is a perspective view of the visor, Figure 2 is a top plan view thereof, and

Figure 3 is a front elevation.

The design consists of an automobile visor of the general shape shown in the accompanying drawings having a relatively wide swell

of more pronounced curvature at its extreme forward edge than throughout the remainder of its width and which follows the contour of the entire forward edge of a visor shaped as shown and which swell at its rear edge merges gradually into the body of the visor to thereby maintain a stream line effect while imparting an appearance of thickness and solidity to the forward portion of the visor.

I claim:

The ornamental design for an automobile head lamp visor substantially as shown and described.

Signed by me, this 11th day of September, 1930.

AUGUSTUS J. FRAME.
